(57) **CLAIM**

The ornamental design for a device for water pipe, as shown and described.

DESCRIPTION

FIG. 1 is a perspective view of a device for water pipe, showing my new design;

FIG. 2 is a front elevational view thereof, the rear elevational view being a mirror image thereof;

FIG. 3 is a left side elevational view thereof; the right side elevational view being a mirror image thereof;

FIG. 4 is a top plan view of the lower portion of the device for water pipe;

FIG. 5 is a top plan view of the upper portion of the device for water pipe;

FIG. 6 is a bottom plan view of the lower portion of the device for water pipe; and,

FIG. 7 is a bottom plan view of the upper portion of the device for water pipe.

The broken lines showing a water pipe in FIG. 1 depict environmental matter and form no part of the claimed design. The device for water pipe is designed to be used with a water pipe for cooling and protection against breakage.
